FOREIGN PATENT DOCUMENTS

CN 201296408 Y 8/2009

Primary Examiner — Elizabeth J Oswecki(74) *Attorney, Agent, or Firm* — Ingenium Patents LLC; Peter R. Kramer

(57)

CLAIM

The ornamental design for a holiday nipper ornament, as shown and described.

DESCRIPTION

The sole FIGURE is a side view of a holiday nipper ornament, showing my new design.

All surfaces not shown form no part of the claimed design. The broken lines of a circle and bottle shown in the drawing form no part of the claimed design.

1 Claim, 1 Drawing Sheet(56)
